Carl Kreuter and Harry Foster Jordan,
Seattle, Wash.

Application September 26, 1950, Serial No. 12,354

Term of patent 14 years

(Cl. D58—15)

To all whom it may concern:

Be it known that we, Carl Kreuter and Harry Foster Jordan, both citizens of the United States and both residing at Seattle, in the county of King and State of Washington, have invented a new, original, and ornamental Design for a Fez Box, of which the following is a specification, reference being had to the accompanying drawing, forming a part hereof.

Figure 1 is a perspective view of a fez box with the cover removed, showing our new design, and

Figure 2 is a perspective view thereof with the cover in closed position.

We claim:

The ornamental design for a fez box, substantially as shown.

CARL KREUTER.
H. FOSTER JORDAN.
